UNITED STATES PATENT OFFICE.

JAYSON K. BOND, OF MILWAUKEE, WISCONSIN, ASSIGNOR TO FEDERAL ASBESTOS & CORK INSULATION CO., OF MILWAUKEE, WISCONSIN, A CORPORATION OF WISCONSIN.

BAFFLE TRAY FOR REFRIGERATED DISPLAY COUNTERS.

Application filed December 1, 1927. Serial No. 237,030.

This invention relates to improvements in baffle trays for refrigerated display counters.

It is one of the objects of the present invention to provide baffle trays for refrigerated display counters which insure a continuous, uninterrupted circulation of air from the counter cooling coils downwardly and forwardly to the front of the counter and then upwardly and rearwardly to the upper portion of the coils, the return circulation being sufficiently high so as to prevent the air from absorbing an excessive amount of moisture from products displayed on the trays within the counter.

15 A further object of the invention is to provide a baffle tray of the class described which is readily removable from a counter and so designed and shaped that it may only be replaced in its correct position, insuring 20 an air space between its rear portion and the coil.

25 A further object of the invention is to provide a baffle tray of the class described of such shape and dimensions as to be shallowest at its inner end adjacent the coil, and increasing in depth toward its forward end portion, the upper rear portion of the baffle also being spaced from the top rear portion 30 of the counter, and said space being greater than the greatest depth of the tray portion, whereby an active circulation of air will be provided over the top of the baffle and downwardly through the coils.

35 A further object of the invention is to provide a baffle tray of the class described having an upwardly angled forward end portion to cause the returning air current to be deflected upwardly to clear the tops of the average produce held on said tray.

40 A further object of the invention is to provide a baffle tray for refrigerated counters which will insure an economical circulation of cold air without a direct contact with the counter contacts, thus avoiding the 45 picking up of moisture from the goods in the course of the direct air circulation.

45 A further object of the invention is to provide a baffle tray of the class described formed of a good conducting material, so 50 that produce thereon receives a high percentage of conducted cold from below the baffle without air circulation from the same source.

A further object of the invention is to provide a baffle tray of the class described 55 having the very highest degree of sanitation and cleanliness and presenting an attractive, neat appearance.

A further object of the invention is to provide a baffle tray for refrigerated display counters which is of very simple construction, is strong and durable and is well adapted for the purposes described.

With the above and other objects in view, the invention consists of the improved baffle tray, and its parts and combinations as set forth in the claims, and all equivalents thereof.

In the accompanying drawing, in which the same reference characters indicate the 70 same parts in all of the views:

Fig. 1 is a cross-sectional view of a refrigerated display counter equipped with the improved baffle trays;

Fig. 2 is a sectional view taken on line 75 2-2 of Fig. 1; and

Fig. 3 is a perspective view of a baffle tray.

Referring now more particularly to the drawing, it will appear that the numeral 5 indicates a refrigerated display counter 80 which is formed with a slightly forwardly inclined insulated bottom 6, an angularly extending glazed front portion 7, slidable doors 8 forming a rear, and a top portion 9. There is also within the counter a longitudinally extending partially enclosed compartment 10 in which is positioned a coil 11 85 by which means the interior of the counter is cooled.

Within the counter and resting on the bottom portion thereof are a plurality of baffle trays 12, one of which is shown in detail in Fig. 3. Said baffle trays are arranged side by side and transversely of the counter. 95 As shown clearly in Fig. 3, each baffle tray is formed with a flat platform portion 13 bent upwardly at its inner end portion at an angle slightly less than a right angle to form a rear portion 14. The platform portion is supported at its side edges by a pair of rails 15 which are narrower at their inner end portions than at their forward end portions, with their lower edges forwardly and downwardly inclined, conforming to 100 the slope of the bottom 6 of the counter, 105

while the upper edges of said rails are slightly less sloping, supporting the top or platform 13 in a slightly forwardly inclined position. The rails 15 at their rear end portions are narrowed and turned upwardly angularly, as at 15', against the rear portion 14. The forward end portions of the rails 15 are tapered or reduced, as at 16. The platform portion, just inwardly of the reduced rail portions 16, is formed with an upwardly and inwardly angled flange 17, of a comparatively small height, which acts as a forward baffle. Each baffle tray is formed of a good conducting material, as iron, and has a porcelain finish to enhance its appearance and to render it easy to clean and sanitary.

As shown in Figs. 1 and 2, the baffle trays are removably positioned adjacent each other within the counter, with the rear rail portions 15' against the coil and the forward tapered portions 16 against the front portion of the counter. This arrangement is such that the trays may only be placed in their correct positions. The portions 15' space the portions 14 from the coil assuring vertical air ducts adjacent the coils which communicate with slightly forwardly inclined ducts between the counter bottom portion and the platform portions of the trays.

In use, produce is displayed on the platform portions of the trays, and the air circulation is as indicated by the arrows in Fig. 1, the air passing into the coil compartment between the tops of the trays and the counter portion 18, then downwardly, being cooled by the coils, and forwardly between the counter bottom and the tray platforms, here cooling the material on the trays by conduction. The air leaves the forward end portions of the trays through the spaces between the tapered ends 16 and circulates upwardly and rearwardly to the coils, being prevented from passing too close to the tray surfaces and from absorbing excessive amounts of moisture from the produce, by the forward baffles 17.

From the foregoing description, it will be evident that the improved baffle trays for refrigerated display counters provide for a rapid, efficient circulation of air within the counter, and are also attractive and sanitary. Also, the trays are of simple and novel construction, and are well adapted for the purposes set forth.

What I claim as my invention is:

1. A baffle tray for refrigerated display counters, comprising a platform portion, a comparatively short front baffle extending upwardly from the front edge of the platform portion, a rear baffle extending upwardly from the rear portion of the platform portion and of a considerably greater height than the front baffle, and spacing rails projecting from said rear baffle and the platform member and extending longitudinally of the latter. 60

2. A baffle tray for refrigerated display counters, comprising a platform portion, a comparatively short front baffle extending upwardly from the front edge of the platform portion, a rear baffle extending upwardly from the rear portion of the platform portion and of a considerably greater height than the front baffle, and spacing rails projecting from said rear baffle and the platform member, the platform portion at its front end terminating short of the rails so as to provide a duct outlet opening. 70

80

3. A baffle tray for refrigerated display counters, comprising a platform portion, a rear baffle portion extending upwardly therefrom, and rearwardly tapered rail members depending from the platform, said rail members also being continued upwardly against said rear baffle portion. 85

90

4. A baffle tray for refrigerated display counters, comprising a platform portion, a rear baffle portion extending upwardly therefrom, and rearwardly reduced rail members depending from the platform and extending forwardly of the front edge of the platform, said rail members also being continued upwardly against said rear baffle portion. 95

100

5. A baffle tray for refrigerated display counters, comprising a substantially horizontal platform portion, a comparatively short front baffle extending upwardly from the front edge of the platform portion, a rear baffle extending upwardly from the rear portion of the platform portion and of a considerably greater height than the front baffle, and rearwardly reduced rail members depending from the platform portion and extending forwardly of the front edge of the same, said rail members also being continued upwardly against said rear baffle, the entire tray being formed of a porcelain coated, heat conducting material. 105

110

In testimony whereof, I affix my signature.
JAYSON K. BOND.
